UNITED STATES PATENT OFFICE.

KARL C. WELLS, OF REDLANDS, CALIFORNIA.

DESIGN FOR A GAS-ENGINE-SPARK-PLUG-CLEANING DEVICE.

44,600.

Specification for Design.

Patented Aug. 26, 1913.

Application filed July 5, 1913. Serial No. 777,595. Term of patent 14 years.

To all whom it may concern:

Be it known that I, KARL C. WELLS, a citizen of the United States, residing at Redlands, in the county of San Bernardino and State of California, have invented a new, original, and ornamental Design for a Gas-Engine - Spark - Plug - Cleaning Device, of which the following is a specification, reference being had to the accompanying drawing, forming part thereof.

The figure is a perspective view of a gas engine spark plug cleaning device, showing my new design.

I claim:

The ornamental design for a gas engine spark plug cleaning device as shown.

KARL C. WELLS.
